Primary Examiner — Garth Rademaker*Assistant Examiner* — Llorellys Martinez-Rivera(74) *Attorney, Agent, or Firm* — Weaver Austin Villeneuve & Sampson(57) **CLAIM**

We claim the ornamental design for an armband, as shown and described.

DESCRIPTION

FIG. 1 is a top view of an armband showing our new design; FIG. 2 is a side view thereof; FIG. 3 is a bottom view thereof; and, FIG. 4 is a perspective view thereof.

The pattern shown within the rounded rectangle in the center of FIGS. 1 and 4 represents a textile mesh. The darker pattern shown on the left sides of FIGS. 1, 2, and 4 represents loop fasteners. The dark pattern shown on the right side of FIGS. 2 and 3 represents hook fasteners.

1 Claim, 2 Drawing Sheets(56)
